UNITED STATES PATENT OFFICE.

EDWARD L. LEINBACH, OF CHICAGO, ILLINOIS.

CONTAINER CLOSURE.

Application filed November 21, 1928. Serial No. 320,782.

This invention relates to improvements in container closures, and one of the objects of the invention is to provide an improved closure of this character which will be spring controlled so that after the same has been opened and then released it will automatically assume a closing position, thereby insuring that none of the contents of the container will be spilled out when the container is carried 10 in a purse or pocket, or when the same is upset, and at the same time will be adapted for free and ready manipulation by the finger of the hand of the operator which grasps the container when it is desired to dispense the 15 contents thereof.

To the attainment of these ends and the accomplishment of other new and useful objects as will appear, the invention consists in the features of novelty in substantially 20 the construction, combination and arrangement of the several parts hereinafter more fully described and claimed and shown in the accompanying drawing illustrating this invention, and in which

25 Figure 1 is a view in longitudinal section of a portion of a container having a closure constructed in accordance with the principles of this invention applied thereto and with the closure in a closing position.

30 Figure 2 is a view similar to Figure 1, showing the closure in an open position.

Figure 3 is a view similar to Figure 2 of a modified form of the invention.

Figure 4 is a perspective view of the form 35 of the invention shown in Figure 3.

Referring more particularly to the drawing the numeral 10 designates generally a container which may be of any desired size and configuration and is provided with external 40 configuration and is provided with external threads 11 encompassing the open end thereof.

A cap 12 formed of any suitable material is provided for the open end of the container and is shaped to form a threaded portion 13 adapted to engage the external threads 11 on

45 the container.

The cap is provided with an opening 14 therethrough having a circumferential flange 15 encompassing the opening and projecting to one side of the cap.

50 This opening 14 may be of any desired size and configuration but is comparatively large with relation to the mouth of the container

so as to permit the free passage of the contents of the container therethrough.

A closure 16 constructed of any suitable 55 material is preferably provided with a depressed portion 17 adapted to fit within the opening 14 when the closure is in the position shown in Figure 1. The portion of the closure 16 which rests upon the cap 12 is preferably of a diameter slightly greater than the diameter of the adjacent portion of the cap so that when the container is grasped in the hand, the thumb of the hand may engage a portion of the periphery of the closure and 60 tilt it to the position shown in Figure 2.

Secured to the closure preferably to the depressed portion 17 thereof, is a member 18 preferably in the form of a bolt or rivet which passes through the closure and is secured thereto in any desired or suitable manner. This member 18 may be of any desired length and is provided on its free end with a head or shoulder 19. A coil spring 20 having any desired number of convolutions and 70 arranged so as to decrease in diameter from one end to the other end of the spring, is provided for controlling the operation of the closure 16. The base of the spring encompasses the flange 15 on the cap 12 and rests 75 against the inner side of the cap while the other end of the spring engages and rests against the shoulder 19 on the member 18, the member 18 passing through the convolutions of the spring 20.

85 The spring is of sufficient stress to normally hold the closure 16 in a closing position or in the position shown in full lines in Figure 1, and the convolutions of the spring 20 are so arranged that when the closure 16 is tilted 90 as is shown in Figure 2, the contents of the container 10 will pass between the convolutions so as to be discharged through the opening 14 in the cap. As soon as the closure 16 is released, it will immediately swing back to 95 the position shown in full lines in Figure 1.

In the form of the invention shown in Figures 3 and 4 the closure 16 is provided with a finger engaging portion 21 which is deflected laterally with respect to the body of the closure and is adapted to extend along the 100 side of the cap 12.

With this form of the invention and when the container 10 is grasped in the hand of

the operator, the closure may be tilted to the position shown in Figure 3, by the engagement of one of the fingers of the hand with the finger engaging portion 21.

- 5 With this improved construction it will be manifest that the normal tendency of the spring 20 is to hold the closure in a closing position and in order to open the closure it is necessary to actuate the same against the 10 stress of the spring, with the result that when the container is carried in a pocket or in a purse all danger of the closure opening and of any of the contents of the container being spilled therefrom, will be obviated.
- 15 While the preferred forms of the invention have been herein shown and described, it is to be understood that various changes may be made in the details of construction and in the combination and arrangement of the 20 several parts, within the scope of the claims, without departing from the spirit of this invention.

What is claimed as new is:—

1. A closure of the character described 25 embodying a cap member having a discharge opening therethrough, a closure for said opening, a projection on the closure extending therefrom and into the container, and a spring encompassing said projection, 30 one end of the spring engaging the said projection and the other end operating against said cap.

2. A closure of the character described 35 embodying a cap member having a discharge opening therethrough, a closure for said opening, a projection on the closure extending therefrom and into the container, and a conical spring encompassing said projection, the larger end of the spring operating 40 against the under face of said cap and the smaller end operating upon the said projection.

3. A closure of the character described 45 embodying a cap member having a discharge opening therethrough, a closure for said opening, said closure being separate from the cap, a spring within the cap, and a shoulder on the closure within the cap, said spring being disposed between the inner 50 face of said cap and said shoulder and operating upon both and tending normally to hold the closure in a closing position with respect to said opening.

4. A closure of the character described 55 embodying a cap member having a discharge opening therethrough, a closure for said opening, said closure being separate from the cap, a spring within the cap, and a shoulder on the closure within the cap, 60 said spring being disposed between the inner face of said cap and said shoulder and operating upon both and tending normally to hold the closure in a closing position with respect to said opening, a portion of said closure extending beyond the periphery of

said cap member to form a finger engaging portion whereby the closure may be unseated against the stress of said spring.

5. A closure of the character described embodying a cap member having a discharge opening therethrough, a closure for said opening, said closure being separate from said cap member, a coiled spring within the cap member, and a shoulder on the closure, said spring being disposed between 75 said shoulder and the inner face of said cap member and operating to normally hold said closure seated, the convolutions of said spring being arranged to permit the passage of the contents of the container therebetween when said closure is unseated.

6. A closure of the character described embodying a cap member having a discharge opening therethrough, a closure for said opening, said closure being separate 85 from said cap member, a stem on the closure and projecting into the cap member, a shoulder on said stem, and a coiled spring 90 encompassing said stem and disposed between said shoulder and said cap member and operating to normally hold said closure seated, the convolutions of said spring being arranged to permit the contents of the container to pass therebetween when said closure is unseated.

7. A closure of the character described embodying a cap member having a discharge opening therethrough, a closure for said opening, said closure being separate from said cap member, a stem on the closure 100 and projecting into the cap member, a shoulder on said stem, and a conical coiled spring encompassing said stem and disposed between said shoulder and said cap member and operating to normally hold said closure 105 seated, the apex of said cone operating against said shoulder and the base against the cap member, the convolutions of said spring being arranged to permit the contents of the container to pass therebetween when 110 said closure is unseated.

8. A closure of the character described embodying a cap member having a discharge opening therethrough, an inwardly projecting flange encompassing said opening, a closure separate from the cap member and having a portion shaped to fit within 115 said opening, a stem on the closure and projecting into the cap member, a shoulder on said stem, and a spring within the cap member 120 disposed between said shoulder and the inner face of the cap member and operating upon both and tending normally to hold the closure seated.

9. A closure of the character described 125 embodying a cap member having a discharge opening therethrough, an inwardly projecting flange encompassing said opening, a closure separate from the cap member and having a portion shaped to fit with- 130

in said opening, a stem on the closure and projecting into the cap member, a shoulder on said stem, and a spring within the cap member disposed between said shoulder and the inner face of the cap member and operating upon both and tending normally to hold the closure seated, a portion of the periphery of the cap member extending be-

yond the periphery of said cap member to form a finger engaging portion whereby the closure may be unseated against the stress of said spring.

In testimony whereof I have signed my name to this specification, on this 19th day of November, A. D. 1928.

EDWARD L. LEINBACH.
